(57) **CLAIM**

The ornamental design for a unmanned ship, as shown and described.

DESCRIPTION

FIG. 1 is a front view of the unmanned ship;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof; and,

FIG. 8 is a second perspective view thereof.

The broken lines in FIGS. 1-8 depict portions of the unmanned ship that form no part of the claimed design.

1 Claim, 8 Drawing Sheets
